UNITED STATES PATENT OFFICE.

ETIENNE DUPLESSIS, OF PARIS, FRANCE.

HAND MACHINE FOR CUTTING OUT SEVERAL THICKNESSES OF FABRIC.

Application filed February 20, 1922. Serial No. 538,034.

To all whom it may concern:

Be it known that I, ETIENNE DUPLESSIS, of 63 Rue Pigalle, Paris, France, have invented a Hand Machine for Cutting Out Several Thicknesses of Fabric, of which the following is a full, clear, and exact description.

The present invention has for its object a hand machine for cutting fabrics in several thicknesses, essentially comprising a cutting blade mounted in a vertical guide post so as to receive, in the latter a rapid to and fro movement, in a vertical direction, by means of a plate and a gear transmission, the rotation of which, in one direction, is obtained by a rocking lever actuated by hand, and, in the other direction, by a returning spring; the various parts of transmission and the controlling lever being carried by a casing which is secured on the guide member of the cutter and is provided with a handle allowing the operator to direct, on the cutting out table, the machine which rests on the said table by means of a horizontal runner provided, on its lower face, with balls or other rolling members.

In order that the invention may be clearly understood, the hand machine, for cutting out fabrics, forming the subject-matter of this invention will be described hereafter with reference to the accompanying drawing in which:

Fig. 1 is a front elevation as seen from the control side of the machine.

Fig. 2 is a rear view.

Fig. 3 is an end view, seen from the side where the cutter is arranged.

Figs. 4 and 5 are, respectively, a front elevation and a vertical section of a modification.

The machine illustrated in the accompanying drawing, essentially comprises, a cutting member, which consists of a sharp vertical blade 1, mounted in a vertical guide post 2 and so arranged in said guide post as to receive, a rapid to-and-fro movement in a vertical direction.

The sharp blade 1 which is, for that purpose, carried by a slide-rod 3 conveniently guided in a slideway 4, which, in the example illustrated Figs. 1 to 3, is secured on one of the faces of a casing 5, carrying the controlling members, and secured to the upper part of the vertical guide post 2 of the cutter which is secured, at its base,

on a runner 6 provided, on its lower face, with balls or other rolling members allowing the operator to easily move the whole of the machine on the cutting table, as will be explained hereafter.

The to-and-fro movement of the slide-rod 3 and cutter 1 which it carries is obtained by means of a control lever 8 rocking on a pivot 9 on the front face of the casing 5 and adapted to be actuated by hand, by the operator, against the action of a returning spring 10, secured at one end to the casing and at its other end to the end of said lever 8.

In the form of device illustrated Figs. 1 to 3, the control lever 8 is integral with a pinion or toothed segment 11, constantly gearing with a small pinion 12, keyed on a shaft 13 mounted in the cheeks or side walls of the casing 5 said shaft carrying a toothed wheel 16 gearing with teeth formed on a shaft 17 also mounted in the cheeks of the casing.

This shaft 17 projects outside the casing 5 and carries, at one of its ends, a crank-plate 18 the crank-pin 19 of which is adjustably connected to the slide-rod 3 by a small link or pitman 20.

Finally, the machine is provided with a presser foot 21 adjustably secured to the casing, so that the vertical position of same may be adjusted according to the thickness of the fabric to be cut out.

In the modification illustrated Figs. 4 and 5, the up and down reciprocating movement of the cutter 1^a in the vertical guide post 2^a is determined by the rotation in one direction or the other, by an eccentric 18^a the strap 20^a of which is directly attached to the slide-rod 3^a carrying the cutter 1^a.

This eccentric, which is conveniently mounted on the bottom of the casing 5^a is held engaged between two toothed segments 16^a freely mounted on an axis 13^a, rendered integral with each other by a common hub and gearing with two pinions 17^a keyed on either side of the eccentric 18^a.

These two segments are normally maintained in the position of rest, illustrated in the drawing, by two coil springs 10^a which, passing on grooved rollers 23 freely rotating about axes 24, secured in the casing 5^a, are attached at one of their ends, to a fixed point of the casing and, at the other end, to the toothed segments 16^a.

The hub connecting the two toothed seg-

ments 16^a forms a small drum to which is attached one end of a control chain 25, the opposite end of which is secured to the hand lever 8^a, as clearly illustrated in the drawing.

The handle 22^a is adapted to form a support for the operator's hand and to constitute at the same time, a guiding member to permit the operator to direct the machine 10 through the pile of fabrics to be cut out, and it is mounted on a pivot 26, about which it may be swung, so as to be capable of being moved towards or away from the lever 8^a, as desired, according to the size 15 of the operator's hand; the said handle 22^a being provided, for that purpose, with a small bolt 27 engaged in a groove 28 of the casing 5^a and which may be fixed in any desired position, by means of a tightening 20 nut.

The above-described machine operates in the following manner:

The various thicknesses of fabric to be cut 25 being maintained one on the other in the usual manner and the machine being placed in position, by hand, so that the sharp edge 30 of the blade 1^a comes into contact with the part of the pile of fabrics to be cut, the operator places the thumb of the right hand 35 on the handle 22^a secured on the casing 5^a and grasps, with the other fingers, the end of the control lever 8^a.

The closing of the hand and fingers produces a rocking movement of the lever 8, 35 against the action of the spring 10, and distends the same, and the opening of the hand allows the spring 10 to contract to return the said lever to its starting position.

These repeated closing and opening movements of the hand determine therefore, by 40 means of the above described gear control, the alternate rotation in one direction and in the other crank-plate 18 and the rapid up and down movements of the cutter 1 which is, at the same time, constantly pushed 45 back towards the fabric to be cut, by the hand holding the machine.

It results from the foregoing, that this machine is very simple and light and that, 50 consequently, it may be constructed at small cost, that it is actuated and manipulated by one hand, in the same manner as cutting scissors, and that it allows the cutting out, without any difficulty the desired number 55 of thicknesses of fabric.

The constructional arrangements described are, of course, given by way of example only, the forms, materials and dimensions of the various constituent parts may be modified 60 without departing thereby from the principle of the invention.

Claims:

1. A hand machine for cutting out several thicknesses of fabric comprising: a horizontal supporting runner,—balls in the said run-

ner projecting under the lower face of the latter,—a vertical guide post integral with the said runner,—a casing carried at the upper end of the said guide post,—a cutter in the said guide post and a slide rod operatively connected to the said cutter,—a crank-plate carried by the casing,—a crank-pin on said crank-plate,—a pitman attached to the said crank-pin and to the slide-rod,—means carried by the casing and arranged to transmit to the crank-plate a movement of rotation in one direction and spring means for rotating said plate in the other direction, and, consequently, an up and down movement to the cutter,—and means for guiding the machine during the cutting out operation.

2. A hand machine for cutting out several thicknesses of fabric, comprising a horizontal supporting member, a vertical guide post integral with the said runner, a casing carried by the upper end of said guide post, a cutter adapted to slide vertically in said guide post, a slide rod connected to said cutter, a crank plate carried by the casing, a crank pin on said crank-plate, a pitman attached to said crank pin and to the slide rod, a combined guide member and control lever pivoted on the casing, gearing in said casing comprising a toothed segment integral with the control lever, a pinion gearing with the toothed segment, a toothed wheel integral with the said pinion, a second pinion integral with the crank plate, a returning spring interposed between the casing and gearing, a handle carried by the casing above the control lever to form a support for the operator's hand and to insure the direction of the machine through the pile of fabric.

3. A hand machine for cutting out several thicknesses of fabric comprising: a horizontal supporting runner,—balls in the said runner projecting under the lower face of the latter,—a vertical guide post integral with the said runner,—a casing carried by the upper end of the said guide post,—a cutter vertically movable in the said post,—a slide-rod operatively connected to the cutter,—an eccentric carried by the casing,—a strap on said eccentric attached to the slide-rod, a control lever pivoted on the casing,—a double toothed segment mounted in said casing,—a chain attached to the said control lever and to the said toothed segment,—a double pinion integral with the eccentric, and a returning spring secured at one end to the casing and at the other end to the toothed segment,—a handle pivoted on the casing above the control lever, a bolt integral with the handle, and fitting in a groove of the casing for adjusting the position of the said handle relatively to the control lever and constituting a support for the operator's hand, and at the same time a member for guiding the machine through the fab-

ric,—and a presser foot adjustable in height on the casing.

4. A hand machine for cutting out several thicknesses of fabric, comprising a supporting runner, a vertically grooved guide post rigidly secured to said runner and projecting upwardly therefrom, a casing carried by the upper end of said post, a cutter slidably mounted in said guide post, inter-

10 connected gear means carried by said casing and operably connected with said cutter to impart a reciprocal movement thereto, a handle member adjustably mounted on said casing and extending rearwardly therefrom, and a control lever pivotally mounted on

15 said casing adjacent said handle mem-

ber and operably connected with said gear means, whereby said handle member and control lever may be manipulated by one hand of the operator to cut the fabrics and guide 20 the cutter.

5. A machine as set forth in claim 4, characterized by an extensible and contractile spring member, operably connected with the casing and the cutter operating gear 25 means, to assist in imparting the reciprocal movement of the cutting blade.

The foregoing specification of my "hand machine for cutting out several thicknesses of fabric", signed by me this 3d day of 30 February, 1922.

ETIENNE DUPLESSIS.
